UNITED STATES PATENT OFFICE.

CHARLES K. ERNST, OF BUFFALO, NEW YORK.

TURN-TABLE.

No. 824,632.

Specification of Letters Patent.

Patented June 26, 1906.

Application filed April 30, 1906. Serial No. 314,377.

To all whom it may concern:

Be it known that I, CHARLES K. ERNST, a citizen of the United States, residing at Buffalo, in the county of Erie and State of New York, have invented a new and useful Improvement in Turn-Tables, of which the following is a specification.

This invention relates more particularly to turn-tables such as are used in garages and stables for automobiles and other vehicles which are not excessively heavy; but the improvements are not necessarily restricted to turn-tables for such use.

The objects of the invention are to produce a turn-table of relatively light but strong and rigid construction which will turn with great freedom without tilting or wobbling, which can be built and installed at a reasonable cost, and which will be stable without requiring a large and expensive pit and foundation.

In the accompanying drawings, consisting of two sheets, Figure 1 is a section of a turn-table embodying the invention. Fig. 2 is a fragmentary plan view thereof, part of the turn-table 4 being removed to expose the supporting-frame thereof. Fig. 3 is a sectional elevation, on an enlarged scale, of the hub and bearing of the turn-table. Fig. 4 is a detail sectional elevation of the turn-table frame, showing the manner of attaching the floor-supporting beams. Fig. 5 is a sectional elevation, on an enlarged scale, of the hub and bearing, showing a slightly different construction.

Like letters of reference refer to like parts in the several figures.

The turn-table consists of a frame A, arranged in a suitable pit to turn horizontally on a bearing in the pit, and a circular floor B, which is supported by the frame substantially flush with the floor or ground of the building in which the turn-table is located. The floor B may be of wood or other material and of any suitable construction.

The frame A is preferably built of metal and composed, as shown in the drawings, of a hub or center casting C, horizontal floor-supporting beams D, which are secured at their inner ends to and project radially from the hub, and a circular rim E, which encircles and is secured to the outer ends of the radial beams. The beams D and rim E are preferably made of channel-beams arranged on edge.

The hub or center casting has a horizon-

tal circular bearing plate or web c, on which the inner ends of the floor-beams rest for a considerable portion of their length, an upright center post c', which extends above 60 the bearing-plate substantially to the tops of the floor-beams and depends for a considerable distance below the bearing-plate, and radial upright webs or braces c², which join the depending portion of the center post to 65 the bearing-plate. These webs or braces c² are wide at their upper ends or extend outwardly for a considerable distance from the center post and taper downwardly, preferably extending to the lower end of the center 70 post. They greatly strengthen the center post and bearing-plate and make the hub very rigid and strong without greatly increasing its weight. c³ represents radial ribs which extend upwardly from the bearing-plate beside 75 the radial floor-beams. Each beam is bolted or otherwise securely fastened to one of these ribs, and the ribs shown are provided with stiffeners or braces c⁴ at one side, joining them to the bearing-plate. 80

The upper portion of the center post c' is preferably provided with lugs d, which overhang the inner ends of the lower flanges of the radial beams to relieve the beam-securing bolts of the strain which would otherwise be 85 thrown thereon by weight on the outer edge of the turn-table.

F represents a metal bearing-box or hollow bearing-casting for the turn-table. The bearing-box is embedded in a concrete or 90 cement foundation f or is otherwise firmly fixed in the pit for the turn-table. Suitable lugs or projections f' are shown on the bearing-box for firmly anchoring it in the concrete foundation. The bearing-box is preferably 95 cylindrical and of sufficient size to receive the depending post c' and braces c² of the turn-table hub and is provided at the edge of its upper open end with a circular race g for bearing-balls G, on which the turn-table bears and is supported. The bearing-plate c of the hub has a depending bearing-flange g' resting on the balls. The bearing-flange preferably depends within a retaining lip or flange h on the edge of the bearing-box 100 and has a conical or beveled face which rests on the balls. The turn-table is supported by and turns on the bearing, which being considerably removed from the axis of the turn-table forms a stable support therefor. 105

A center bearing is also provided between the lower end of the center post and bearing-

box. This center bearing preferably consists of a hardened-steel stud 1, removably secured to the bottom of the bearing-box and entering a hole in the lower end of the center post. 5 In the construction shown in Figs. 1 and 3 the stud is screwed into a removable hardened-steel plate *i*, which is seated in a hole in the bottom of the bearing-box and secured by bolts or otherwise, and bearing-balls *i'* are 10 arranged between the stud and center post, the balls working and being confined in circular grooves or races in the plate *i* and lower end of the center post. This center bearing is not intended to carry any of the weight of 15 the turn-table, but acts as a centering or steadyng bearing therefor to hold the same from tilting and to prevent the possible disengagement of the bearing-flange *g'* from the balls *G* of the supporting-bearing at the upper 20 end of the bearing-box. Both the supporting and centering bearings are provided on the bearing-box, and the center post and its braces are confined within the box. This box entirely supports the turn-table and is 25 the only part requiring a foundation. No supporting wheels or tracks at the outer edge of the turn-table are necessary.

Fig. 5 shows a slightly different bearing construction, in which *G'* represents the balls of 30 the supporting-bearing. These balls, as in the construction before described, are located in a circular groove in the upper end of the bearing-box *F'*; but the bearing-plate *c* has a depending bearing flange or rim *k*, which surrounds the bearing-balls and is provided with an inner beveled bearing-face *k'* for the balls. In addition to this supporting-bearing an antifriction retaining-bearing is provided, 40 consisting of a second circular row of balls *l*, confined in a groove or race in a ring *l'* and bearing upwardly against a downwardly-facing beveled portion of a flange *l''* on the upper end of the bearing-box. This groove-ring is removably secured by bolts or otherwise to 45 the depending flange *k* of the bearing-plate and is of sufficiently large diameter to be slipped over the lower end of the bearing-box, or this ring could be made in sections. The retaining-bearing acts, in conjunction with 50 the center bearing *M* between the lower end of the center post and box, to prevent the disengagement of the turn-table from its supporting-bearing and to insure its rotation in a horizontal plane. Antifriction-balls are 55 not required in this construction for the center bearing *M*. In this construction, like the other, the turn-table is entirely supported by the bearing-box.

I claim as my invention—

60 1. The combination of a fixed hollow bearing-box having an open upper end provided with a circular race, a turn-table arranged above the bearing-box and having a center post depending into the bearing-box, anti-

friction supporting-bearings for the turn-table arranged between the same and the circular race at the upper end of the bearing-box, and a center bearing between the lower end of said center post and the lower portion of the bearing-box, substantially as set forth. 65

2. The combination of a fixed hollow metal bearing-box having an open upper end provided at its rim with a circular race, a turn-table arranged above the bearing-box and having a center post depending into said box, 70 antifriction supporting-bearings for the turn-table arranged in said circular race and bearing against a circular face on the turn-table, and a center bearing for the turn-table consisting of a bearing member removably secured to the bottom of the bearing-box and provided with means for engaging the lower end of said center post, substantially as set forth. 75

3. The combination of a fixed hollow metal bearing-box having an open upper end provided with a circular race, a turn-table arranged above the bearing-box and having a center post depending into said box, braces for said center post also arranged within said bearing-box, antifriction supporting-bearings for the turn-table arranged between the same and said circular race at the upper end of the bearing-box, and a center bearing between the lower end of said center post and the lower portion of the bearing-box, substantially as set forth. 80

4. The combination of a fixed hollow bearing-box having an open upper end, a turn-table having a horizontal bearing-plate arranged above the bearing-box, a center post depending below said bearing-plate into the bearing-box, braces connecting said bearing-plate and the depending portion of the bearing-post and located within the bearing-box, 100 antifriction-bearings arranged between the upper open end of the bearing-box and said bearing-plate, and a center bearing between the lower end of said center post and the lower portion of the bearing-box, substantially as set forth. 105

5. The combination of a fixed hollow bearing-box having an open upper end, a turn-table frame comprising a hub, and floor-supporting members secured to said hub, said hub consisting of a horizontal bearing-plate provided with upwardly-projecting parts to which the floor-supporting members are secured, and a center post which depends from said bearing-plate into the bearing-box, and braces connecting the center post and bearing-plate and located within the bearing-box, 115 antifriction-bearings arranged between the open upper end of the bearing-box and said bearing-plate, and a center bearing between the lower end of said center post and the lower portion of the bearing-box, substantially as set forth. 120

6. The combination of a fixed hollow bearing-box having an open upper end, a turn-table frame comprising a hub, radial floor-supporting members secured to said hub, and a rim connecting the outer ends of said floor-supporting members, said hub consisting of a horizontal bearing-plate and a center post depending from said bearing-plate into the box-bearing, parts extending upwardly from said bearing-plate to which the said radial floor-supporting members are secured, and braces connecting said center post and said bearing-plate and located within the bearing-box, antifriction-bearings arranged between the upper end of the bearing-box and said bearing-plate, and a center bearing between the lower end of said center post and the lower portion of the bearing-box, substantially as set forth.

15 7. The combination of a fixed hollow bear-

ing-box having an open upper end provided with a circular race, a turn-table arranged above the bearing-box and having a center post depending into the bearing-box, antifriction supporting-bearings for the turn-table between the same and the circular race at the upper end of the bearing-box, antifriction retaining-bearings arranged between the upper end of the bearing-box and a depending portion of the turn-table, and a center bearing between the lower end of said center post and the lower portion of the bearing-box, substantially as set forth.

25 Witness my hand this 27th day of April, 1906.
